INVENTOR.

UNITED STATES PATENT OFFICE.

J. HERBERT CHASE, OF MONTREAL, CANADA.

MECHANICAL MUSICAL INSTRUMENT.

SPECIFICATION forming part of Letters Patent No. 360,280, dated March 29, 1887.

Application filed July 11, 1882. Serial No. 66,383. (No model.) Patented in England September 29, 1882, No. 4,633.

To all whom it may concern:

Be it known that I, J. HERBERT CHASE, of Montreal, in the county of Montreal and Dominion of Canada, have invented certain new and useful Improvements in Mechanical Musical Instruments, (for which I have obtained patent in Great Britain, No. 4,633, dated September 29, 1882,) of which the following is a full, clear, and exact description.

10 This invention relates to mechanical musical instruments using a perforated music-sheet as the medium for controlling, as it travels through the instrument, the sounding of the reeds or other sounding devices employed, the 15 "orguinette," so called, being a well-known illustration of such instruments.

20 The invention mainly consists in a valve of flexible material and substantially circular form to the bellows of musical instruments, secured in position at its central portion only and left free at its edges to vibrate, in combination with a fender, also secured at its central portion.

25 The invention also consists in the combination, with bellows and exhausters or feeders located in pairs alongside of each other, and those of each pair one above the other and connected together to work laterally, of a wind-chest having two separate compartments, both 30 in communication with said bellows, one of the compartments being in communication with the exhausters and the other with the race-way and reed-chest of the instrument.

35 The invention also consists of other features, which will be hereinafter described and claimed.

In addition to the above this invention embraces other features of improvements, which will hereinafter fully appear.

40 In the accompanying plate of drawings, a mechanical musical instrument of the present improved construction is illustrated, with a system of bellows for sounding reeds by exhausting air through them.

45 Figure 1 is a plan view; Fig. 2, a side elevation with the side of the casing to the instrument removed; Fig. 3, a transverse vertical section on line 3 3, Figs. 1 and 4; Fig. 4, a longitudinal vertical section on line 4 4, Fig. 5c 1; Fig. 5, a transverse vertical section on line 5 5, Fig. 4, and below the line of travel of the perforated music-sheet through the instru-

ment; Fig. 6, a longitudinal vertical section on line 6 6, Fig. 3, of the parts shown in Fig. 5; Figs. 7 and 8, respectively, longitudinal, 55 horizontal, and vertical sections, on an enlarged scale, in detail, of the reed-chest, constructed, also, as a tremulant and swell-box; Figs. 9 and 10, respectively, detail plan and section of the valves and their fenders to the 60 bellows, &c. Fig. 11 is a transverse sectional view of the reed-chest, showing a construction thereof in accordance with this invention, and hereinafter particularly referred to.

In the drawings, A represents the casing or 65 cabinet of the instrument, composed of sides B, ends C, and top D.

E is the bellows or reservoir, occupying the lower portion of the casing A. The bellows or reservoir E is horizontal, and its upper side 70 board, F, is fixed to a longitudinal vertical central board, G, secured to the under side of the casing-top D, and its lower side board, H, is arranged to open from and close against the upper side board, F. The bellows or reser- 75 voir E, otherwise, is constructed and arranged and of itself works from the operation of ex- hausters J J' J² J³, combined therewith as hereinafter described.

The exhausters J J' J² J³ are in two pairs, 80 arranged, those of each pair, one above the other, with an open space, a, between and upon opposite sides of the vertical central board, G, and between it and the sides B of the casing A. Of each pair of exhausters the 85 lower ones are attached to the upper fixed board, F, of the bellows or reservoir E, and their moving sides b open from and close against said board F. The upper exhausters are attached to the under side of the casing- 90 top D, and their moving sides c open from and close against said top D. The so-working sides b and c, respectively, of each pair of ex- hausters have a series of air-passages, d, through them for air to pass out as they close. These 95 air-passages d of each exhauster are similarly grouped about a common center, and each group is covered by a leather or other similar flexible valve, f, secured in place at its central portion only by a screw, f⁴, and thus adapted 100 to open outwardly for air to pass out only from the exhausters. Each flexible valve f is guarded by a plate or fender, g, made of metal or other suitable rigid material, and shaped

to cover to a greater or less extent the flexible valve. The face of each fender toward the valve is made sufficiently flaring, as shown at *l*, (giving it an outer concave and an inner convex shape,) to allow the valves to open to the necessary extent in the operation of the bellows to which they are attached. The fenders *g* protect the valves and keep them always in their best position for operation.

10 The two moving sides *b c* of each pair of exhausters *J J' J² J³* are connected by a rod, *m*, pivoted to each, and the moving side of each of the lower exhausters is connected by a separate pitman-rod, *K*, to separate crank-15 arms *n* of a common horizontal driving-shaft, *L*. The driving-shaft *L* extends across and from side to side of the instrument, and between said sides it acts as a feed-roll for feeding the perforated music-sheet *M* through the 20 instrument.

N is a presser-roll above the feed-roll *L*, for confining the music-sheet to the feed-roll.

The exhausters of each pair, arranged one above the other and connected together and to 25 cranks of a common driving-shaft, as above described, open and close alternately, and those of each pair work within substantially the same space, between the under side of the casing-top *D* and the stationary part *F* of the 30 bellows *E*, and for each pair of exhausters to work in pairs after each other, in lieu of simultaneously, their operating-cranks of the common driving-shaft are arranged at different 35 points in the circle of rotation of the driving-shaft.

o are air-passages grouped about a common center in the stationary board of bellows or reservoir *E*, and connecting such bellows with the lower exhauster of each pair of exhausters, 40 and *p* are air-passages grouped about a common center in the casing-top *D*, and connecting the upper exhauster of each pair of exhausters with one compartment, *O*, of a wind-chest, *O P*. The wind-chest *O P* is attached 45 to and across the upper side of the casing-top *D*. The several groups of air-passages *o p* are each provided with flexible valves *f* and fenders *g*, and these valves open inwardly and are constructed and arranged and operate 50 the same as the valves and fenders to the groups of air-passages *d* of each of the exhausters *J J' J² J³*, hereinbefore described.

r is a vertical air-passage leading from the compartment *O* of the wind-chest *O P*, through 55 the central vertical block, *G*, into the bellows or reservoir *E*. The compartment *P* of the wind-chest *O P* is alongside of and parallel to but separate from the other compartment, *O*.

t are vertical air-passages leading from the 60 wind-chest compartment *P*, through the central vertical board, *G*, into the bellows or reservoir *E*.

The upper and outer surface of the wind-chest *O P* makes the usual bed or raceway, 65 *Q*, of the instrument, for the travel of the perforated music-sheet, by the rotation of the feed

and presser rolls, when such rolls are operated by the crank-handle *R*, and it has a slotted opening, *u*, which runs across the instrument from side to side, and opens to the raceway *Q* 70 and to the compartment *P* of the wind-chest *O P*.

S are parallel cheek-pieces, one at each end of the wind-chest. These cheek-pieces run lengthwise of the instrument, and are secured 75 in place in any suitable manner, and their projections *v* above the bed or raceway *Q* make guides for the opposite edges of the music-sheet in its travel through the instrument.

T is a framing or lid composed of side pieces, 80 *w*, end pieces, *x*, and top *y*. This lid *T* rests at each side upon the upper edges of the cheek-pieces *S*, and at the rear end of the instrument it is hung by headed pins *a²* in horizontal slots *b²* of posts *c²*, attached to the cheek-pieces *S*, 85 and at the forward end it is confined in place by studs *d²*, which enter into and engage with holes *f²* in vertical spring-arms *U*, secured to the casing-top *D*. This hinging and attachment of the lid *T* enables it to be freely and 90 easily attached and detached and opened and closed from its seat or rest upon the cheek-pieces by simply releasing it from its spring-arms and swinging it upon its hinges without necessarily detaching it from its hinging-posts 95 *c²*. The lid *T* carries the presser-roll *N*, and the cheek-pieces the feed-roll; and when the lid is raised on its hinges or removed the presser-roll is lifted from the feed-roll.

V is a reed-chest, and *g²* are the reeds. Each 100 reed is made, as usual, of a block, *g³*, and a vibrating tongue, *g⁴*. The reeds are severally placed alongside each other against the inner surface of the bottom board, *h²*, of the reed-chest, and in this position they are severally secured 105 by headed screws *l²* passing through each end of the reed-blocks into the bottom board. The bottom board, *h²*, has a series of separate air-passages, *m²*, through it, severally leading to the vibrating tongues of the reeds, and these 110 air-passages are each of a length and width to leave the reed-tongues from the toe for a portion of their length toward the heel open to said air-passages *m²*.

n² are the reed-cells, one to each reed. These 115 reed-cells are above the reeds in the reed-chest, and each cell has parallel upright walls *r²*, which run lengthwise of the reeds along and over the line of juncture of the adjoining edges of the reed-blocks *g³*, and also a top wall, *s²*. 120 All the upright and side walls, *r² s²*, preferably, are in one piece or block of wood, *W*, which is placed against the inner face of one of the side walls of the reed-chest, and the upright walls *n²* are over the lines of juncture of the adjoining edges of the reed-blocks, and all

so as to make a series of separate reed-cells, 125 each of which covers and incloses a tongue of a reed from its toe for a portion of its length toward its heel, and is open at the end *t²* toward the heel, but closed at all other parts. This block *W*, containing the reed-cells, can be 130

easily removed from the reed-chest, thus giving free access to the reeds for tuning them, replacing broken reeds, or other necessary purposes.

5 The reed-chest is closed by a cover, X, secured in place by screws v^2 , or other suitable fastening devices, preferably such as are readily detachable and attachable from time to time, as may be desired. This cover X at each end 10 projects beyond the ends of the reed-chest, and it has four circular air-holes, w^2 , through it, arranged at equal distances apart and in a straight line along the length of the cover, and opening to the inside of the reed-chest directly 15 above the reed-cell block W. The cover X also has a single circular air-hole, x^2 , which opens to the reed-chest, and is located at one side of the line of air-holes w^2 , and in line with a closed portion of the cover between two 20 of said air-holes w^2 . This air-hole x^2 , located singly, as described, has within the reed-chest V a tremulant valve, Y, constructed and arranged, as usual, to freely vibrate within the reed-chest from the passage of air through 25 said air-hole into and thence out of the reed-chest through its reed-cells, reeds, and air-passages m^2 .

Z is a slide board, having a slot, a^3 , at each end, by which it is arranged to slide lengthwise upon the cover X of the reed-chest over headed screw guide-pins b^3 , suitably located therefor.

d^3 are three circular air-holes through the slide-board Z, and in a straight line along its length, and at equal distances apart, and of a shape corresponding to three of the four air-holes w^2 through the cover of reed-chest. The air-holes d^3 are so arranged, and the slide-board Z and its slots are of such length, respectively, in relation to the location of the guide-pins, that the slide-board in being moved in one direction, and to the full extent of its movement in such direction, then fully closes the four air-holes w^2 through the cover of the 45 reed-chest, and in being moved in the other direction, and to the full extent of its movement in such direction, then fully opens said four air-holes w^2 —three of them because of their being then coincident with the three 50 holes d^3 in said slide, and the fourth and remaining one because said slide has passed beyond it. The slide Z has also a single air-hole, f^3 , corresponding in shape, size, and location to the single air-hole x^2 through the 55 cover of the reed-chest. The single air-holes f^3 x^2 are relatively situated to have the single air-hole x^2 , leading through the cover of and into the reed-chest, open when the four other air-holes, w^2 , into said reed-chest are closed, 60 and to have said single air-hole f^3 of the cover closed when said four air-holes w^2 are opened. This relative opening and closing of the air-holes through the cover of the reed-chest are secured by moving the slide-board, as before 65 explained.

g^3 is a knob attached to slide-board for convenience in operating it. The reed-chest V,

constructed and arranged in its several parts as described, is placed within an opening, h^3 , of the hinged lid T, made of suitable shape to 70 receive it, and it rests by its bottom board upon the bed or raceway Q, or, if the perforated music-sheet is in the instrument upon and over the raceway, then upon it, (the music-sheet.) When the reed-chest is so placed its 75 several air-passages m^2 , leading to its reeds, are directly over the slot u of the raceway Q, which leads to the compartment P of the wind-chest O P; and, again, the end projections, l^3 , of its top board, X, overlap each side of the lid 80 T, and thus prevent it from dropping through and out of the lid-opening h^3 in one direction only, should the lid be raised from its position of rest by swinging it upon its hinges, or be detached from the instrument. The dropping 85 of the reed-chest in either direction from its opening of the lid T can be also prevented with a button, m^3 , hung to the inside of the lid T, and a notch, n^2 , in the proper side of the reed-chest, for an interlock of the button with 90 it. (See Fig. 4.)

The peculiar construction of the reed-cells n^2 and the arrangement of their walls r^2 directly upon the reed-blocks, together with the arrangement of the reed-blocks alongside of each 95 other, while giving each reed a separate cell, secure a great economy in space and reduce the width of the music-sheet requisite between its several rows of perforations, and as a consequence considerably reduce the music-sheet 100 in its whole width, as compared with the music sheet necessary when the reeds are within or between the walls of separate reed-cells, as heretofore.

Again, by the construction of the cover T to 105 the reed-chest with air-passages w^2 and a single air-passage, x^2 , and tremulant valve Y, in combination with a slide, Z, constructed and arranged to open and close said air-passages, as described, swell and tremulant effects can be 110 obtained in the sounding of the reeds from the passage of a perforated music-sheet through the instrument, and the working of the wind mechanism herein described, as is plainly obvious without further particular description herein. 115

As the reed-chest V and lid T are arranged together, as described, the reed-chest is free to lift and lower within the lid, as necessary, and also to be easily and readily attached and detached, as desired. 120

Although the reed-chest has been described as adapted for both swell and tremulant effects, the construction of the reed-chest for either one or the other of such effects may be omitted, if so desired. 125

The connection of the upper exhausters, J J^2 , with the compartment O of a wind-chest, O P, and such compartment O directly with the bellows E, and the connection of the lower exhausters directly with the bellows and the bellows with the other compartment, P, of the wind-chest O P, equalizes the drawing of air by the bellows through the reeds, in consequence 130 of the operation of each set of exhausters so

connected with the bellows, and in that respect the two compartments of the wind-chest are advantageous, although, as is obvious, the two compartments may be made into one, if so desired, without materially or practically affecting the working of the mechanism herein described to sound the reeds.

The arrangement of the exhausters and of the bellows or reservoir herein described obviously economizes space while securing most effective wind mechanism; and, again, the attachment described of the valves to the exhausters and bellows obviously is most simple, cheap, effective, durable, and practical.

15 If desired, feeders or force-bellows may be substituted for the exhausters or exhaust-bellows herein particularly described, of course making the obvious and well-known necessary changes in the arrangements of the valves and other parts; and in case of substitution and changes such as stated, the description herein given of the exhausters or exhaust-bellows is as well applicable to feeders or force-bellows.

20 The reeds arranged according to this invention have been particularly described as provided with separate cells; but while separate cells are preferable, fair tones may be secured from them by arranging in the reed-chest a partition, A², substantially parallel to the reeds, but preferably on an incline. (See Fig. 11, which is a sectional view in detail in illustration thereof.) A partition so arranged acts to qualify the tones of the reeds substantially the same as the separate cells for the reeds.

25 The partition A² in the reed-chest just above described, as also the parts of the reed-chest making the separate reed-cells, may be either permanently attached to the reed-chest or so attached as to be easily attached and detached at pleasure. The latter method is preferable, for reasons hereinbefore given in connection with the description of the block W, which contains the separate reed-cells.

30 The reed-chest having reeds arranged alongside of each other and a construction to qualify the tones of the reeds, all substantially as described, may be permanently secured in its position in the instrument, in lieu of being confined in place, as particularly described and shown; but obviously it is preferable to arrange it within the instrument for its easy insertion and removal.

Having thus described my invention, what I

claim, and desire to secure by Letters Patent, 55 is—

1. A valve of flexible material and substantially of circular form, attached to the bellows of musical instruments, and secured in position at its central portion only and left free at its edges to vibrate, in combination with a fender, g, also secured at its central portion, substantially as and for the purpose described.

2. In a mechanical musical instrument, the combination, with bellows E and exhausters or feeders located in pairs alongside of each other, and those of each pair one above the other and connected together to work alternately, of a wind-chest, O P, having two separate compartments, both in communication with said bellows, and the one O in communication with the exhausters and the one P with the raceway and reed-chest of the instrument, all substantially as and for the purpose described.

3. In a mechanical musical instrument, the combination, with a perforated music-sheet, of a reed-chest, V, having its reeds g² arranged alongside of each other, in combination with cells n² in a movable block, W, for each reed, constructed and arranged in relation to the reeds substantially as described, for the purpose specified.

4. In a mechanical musical instrument, the combination, with a removable lid, T, having an opening, h³, of a box or chamber of a shape corresponding to fit within said opening, and to be secured therein from accidental escape in the handling of the lid by a fastening device, substantially as and for the purpose specified.

5. In a mechanical musical instrument, the combination, with the wind-chest and bellows E, of one or more pairs of exhausters or feeders, J J' J² J³, located between said bellows and wind-chest, all so arranged that one exhauster of each pair exhausts directly from the wind-chest and the other exhauster of each pair exhausts directly from the bellows.

In testimony whereof I have hereunto set my hand in the presence of two subscribing witnesses.

J. HERBERT CHASE.
